DOOR OPERATING FOOT PEDAL

George W. Melcher, Bally, Pa., assignor to Bally Case and Cooler, Inc., Bally, Pa.

Filed Dec. 14, 1962, Ser. No. 72,865

Term of patent 14 years

(Cl. D67—3)

I claim:

The ornamental design for a door operating foot pedal, as shown.
